(57) **CLAIM**

The ornamental design for a display screen or portion thereof with transitional graphical user interface, as shown and described.

DESCRIPTION

FIG. 1 is a front view of a display screen or portion thereof with transitional graphical user interface showing a first image of the claimed design.

FIG. 2 is a second image thereof; and,

FIG. 3 is a third image thereof.

The outermost evenly spaced broken lines in the drawings show the electronic device, which is the environment of the design and forms no part of the claimed design. The dot-dash broken lines showing the display screen or portion thereof forms no part of the claimed design. The remaining broken lines showing portions of the graphical user interface form no part of the claimed design.

The appearance of the transitional image sequentially transitions between the views of FIGS. 1-3. The process or period in which an image transitions to another forms no part of the claimed design.
